UNITED STATES PATENT OFFICE.

WILLIAM TAYLOR DICKEY, OF NORTHWEST, VIRGINIA.

CONCRETE TIE.

1,158,790.

Specification of Letters Patent.

Patented Nov. 2, 1915.

Application filed February 2, 1915. Serial No. 5,758.

To all whom it may concern:

Be it known that I, WILLIAM T. DICKEY, a citizen of the United States, residing at Northwest, in the county of Norfolk and State of Virginia, have invented a new and useful Concrete Tie, of which the following is a specification.

The device forming the subject matter of this application is a tie and the invention aims primarily, to provide novel means for securing the rail to the tie, so that the rail may have a slight vertical movement.

Another object of the invention is to provide a tie so constructed that a fastening means of the sort hereinafter described may be employed in connection therewith.

A further object of the invention is to provide novel means whereby rails, the base flanges of which are of different widths, may be used.

It is within the scope of the disclosure to improve generally and to enhance the utility of devices of that type to which the present invention appertains.

With the above and other objects in view which will appear as the description proceeds, the invention resides in the combination and arrangements of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 shows in top plan, a tie constructed in accordance with the present invention; Fig. 2 is a section on the line 2—2 of Fig. 1; Fig. 3 is a cross section on the line 3—3 of Fig. 2; Fig. 4 is a perspective view depicting the primary abutment; Fig. 5 is a perspective view depicting the secondary abutment; Fig. 6 is a perspective view showing the tie plate; Fig. 7 is a cross section similar to Fig. 2 but disclosing a modified form of the invention; Fig. 8 is a side elevation showing a modified form of fastener; Fig. 9 is a perspective view showing a still further modification of the fastener.

In carrying out the present invention there is provided a tie denoted generally by the numeral 1. The tie 1 may be fashioned from any desired material, but preferably is made from concrete. The tie, as shown in Fig. 3, may be equipped with a longitudinal cavity 2, and if the tie is made of concrete, a suit-

able reinforcement 3 of any desired form may be provided. The longitudinal, lower edges of the tie 1 preferably are rounded slightly as shown at 4, to facilitate the tamping.

In its upper face, the tie 1 is provided adjacent its end with a transverse recess or groove 5, the recess or groove 5 including a lateral extension 6. Resting in each recess or groove 5 is a tie plate 7. The tie plate 7 ordinarily is fashioned from wood or fiber, in order that it may have some resiliency and act as a cushion, although any desired material may be employed in the making of the tie plate 7. The tie plate is provided with a lateral lug 8 which fits closely in the extension 6 of the recess 5 of the tie, thus to prevent the tie plate or cushion from moving transversely of the tie. In the opposite edges of the tie plate 7 and adjacent its ends, openings or notches 9 are formed, as shown best in Fig. 6.

In the upper face of the tie 1 and aligned with the notches 9 in the tie plate 7, longitudinally of the tie, elongated seats 10 are formed. The remote ends of the seats preferably are enlarged as shown at 11, the walls of the enlarged portions 11 of the seats 10 being shown as disposed in converging relation. In the side walls of the tie 1, openings 12 are fashioned, for a purpose which will be set forth hereinafter.

Supported upon the tie plate or cushion 7 is a rail 22. Disposed in the remote ends of the seats 10 are primary abutments denoted by the numeral 14. Each primary abutment, as shown in Fig. 4, comprises an upstanding head 15 and a foot 17 the edges of the head 15 ordinarily being beveled as shown at 16 to conform to the converging walls of the parts 11 of the seats 10, as will be understood best from Fig. 1. The foot 17 of the primary abutment 14 is provided with a longitudinal slot 18. Cooperating with each primary abutment 14 is a secondary abutment 19 which comprises an upstanding head 20 and a foot 21.

Disposed in each seat 10 is a vertically movable fastener 23, the same including a finger 24 which overhangs and engages the base flange of the rail 22, the opposed fasteners 23 at their adjacent or inner ends being engaged with the notches 9 of the tie plate, as will be understood when Fig. 2 is compared with Fig. 6. Each fastener 23 is provided with a longitudinal slot 25, the re-

mote ends of the fasteners coöperating with the secondary abutments 19 as will be understood from Fig. 2.

The fasteners are held in place by means 5 of securing elements, the same being shown in the form of bolts extended upwardly through the tie 1 and passing through the slots 25 in the fasteners 23. Mounted on the upper ends of the bolts 26 are movable 10 members 27 in the form of nuts, and interposed between the nuts 27 and the fasteners 23 are compression springs 28, the latter bearing against washers 29 which engage the upper faces of the fasteners 23. Each bolt 15 or securing element 26 terminates in a head 30 which bears against the tie 1 at the upper wall of the opening 12, it being possible to insert the bolts 26 upwardly through the tie, owing to the presence of the openings 12.

20 Especial attention is directed to the fact that when the parts are arranged as shown in Fig. 2, the rail 22 is permitted a slight vertical movement, owing to the fact that the springs 28 are provided, it being a common and well known fact that concrete ties 25 have heretofore met with but a limited approval, owing to the fact of their extreme rigidity.

The fasteners 23 may be moved toward 30 and away from each other, owing to the presence of the slots 25, the object in this operation being to permit the use of rails the base flanges of which are of different dimensions, and, under some circumstances, 35 to permit an adjustment of the gage of the track. In this connection, the function of the abutments 14 and 19 will be clearly understood, it being possible to remove one or both of the abutments, should occasion demand. In this particular, attention is directed to the fact that the secondary abutment 19 may be dispensed with entirely, should circumstances demand.

In Fig. 7 of the drawings, the invention 45 has been shown in connection with a guard rail. In Fig. 7, the parts hereinbefore described remain substantially unchanged. The tie is shown at 31, the abutments at 32 and 33, the fasteners at 34 and 35, and the bolts 50 at 36, the springs appearing at 37. The openings in the tie which receive the bolts are denoted by the reference character 38 and the tie plate appears at 39, the same supporting the main line rail 40. The guard 55 rail is shown at 41 and is engaged by the fastener 34, the main rail 40 being engaged by the fastener 35. If desired, a filler or clamp 42 may be interposed between the rails 40 and 41, the filler being held in place 60 by bolts 43. A person skilled in maintenance of way operations, will understand readily that the filler 42 may be replaced by any equivalent structure.

At a joint, where a fish plate is used, the 65 fastener may be modified as indicated at 44

in Fig. 9, the fastener 44 being slotted as shown at 45 and comprising a finger 46. In the angle of the fastener and below the finger 46 is located an integral lug 47 adapted to be received in the spike notches of the fish 70 plate or rail brace (not shown).

At curves, the fastener 48 of Fig. 8 may be used, the same being slotted as indicated at 52 and comprising a head 49 recessed on its under edge as shown at 50, to receive the 75 base flange of the rail, and notched along its upper edge as shown at 51 to coöperate with the ball of the rail.

The tie herein disclosed is practically indestructible and will outlast many wooden ties. The cost of the tie is nominal and probably will not exceed the cost of a first class wooden tie. The labor incident to maintaining the track in a perfect condition will be lessened, owing to the fact that the 80 ties need not be replaced frequently. The fastening means is so constructed that it will grip and hold the rail, yet permitting a slight vertical movement of the rail, as hereinbefore described. However, the rails cannot spread or work loose on the ties. The device is so constructed that it may be adjusted to fit any size of rail. When the rails wear off, they can be adjusted to the proper gage, through the instrumentality of the 85 structure hereinbefore described. All bolts and other fastening means can be inserted and removed without disturbing the position of the tie in the ballast or jacking up the track. If the rail wears down in the tie, the fasteners 23 will follow the rail and hold the same securely, owing to the presence of the springs 28. The fastening means forming a part of this invention may be applied 90 to any kind of a tie whether the same be made of metal or concrete or be a composite 95 tie.

Having thus described the invention, what is claimed is:

1. In a device of the class described, a tie 110 provided with a recess; a rail disposed above the tie; a fastener vertically movable in the recess and engaging the rail, the fastener being guided vertically by the walls of the recess; a securing element engaged at its lower end with the tie and extended above the fastener; a spring engaging the fastener; and an adjustable member on the securing element and coöperating with the spring.

2. In a device of the class described, a tie 115 provided with a seat; a tie plate resting on the tie and provided with a notch alined with the seat; a rail resting on the tie plate; a fastener located in the seat and engaged with the notch of the tie plate and with the rail; and means for securing the fastener to the tie.

3. In a device of the class described, a tie 120 provided with a seat; a tie plate resting on 125

the tie and equipped with a notch alined with the seat; a rail supported on the tie plate; a fastener vertically movable in the seat, one end of the fastener being engaged 5 with the notch in the tie plate and with the rail; a removable abutment interposed between the other end of the fastener and one end of the seat; a securing element engaged at its lower end with the tie and extending 10 upwardly through the fastener; a spring surrounding the securing element and bearing on the fastener; and an adjustable member on the securing element, the adjustable member coöperating with the spring.

15 4. In a device of the class described, a tie provided with a transverse recess having a lateral extension, the tie being provided with a longitudinal seat; a tie plate resting in the recess and including a lateral lug engaged in 20 the extension of the recess, the tie plate being provided with a notch alined with the seat;

a rail resting on the tie plate; a fastener located in the seat and engaged with the notch of the tie plate and with the rail; and means for securing the fastener to the tie. 25

5. In a device of the class described, a tie provided with a seat, one end of which is enlarged; an abutment in the seat and including a head engaged in the enlarged portion of the seat to prevent a shifting of the 30 abutment; a rail upheld by the tie; a fastener in the seat and coacting with the rail and with the abutment; and means for securing the fastener to the tie.

In testimony that I claim the foregoing 35 as my own, I have hereto affixed my signature in the presence of two witnesses.

WILLIAM TAYLOR DICKEY.
